United States Patent Office

Des. 193,118
Patented June 26, 1962

193,118

PACKAGING CONTAINER OR SIMILAR ARTICLE

John Donald Bostrom, Niles, Ill., assignor to Poster Packaging, Inc., Chicago, Ill., a corporation of Delaware

Filed Mar. 16, 1961, Ser. No. 64,338

Term of patent 14 years

(Cl. D58—11)

FIG. 4

FIG. 2

FIG. 3

FIGURE 1 is a perspective view of a packaging container or similar article embodying my new design;

The essential features of the design are shown in full lines.

I claim:

The ornamental design for packaging container or similar article, as shown and described.
